UNITED STATES PATENT OFFICE

122,972

DESIGN FOR A BLOUSE

Arnold R. Salzenstein, Peoria, Ill.

Application March 21, 1940, Serial No. 91,130

Term of patent 3½ years

To whom it may concern:

Be it known that I, Arnold R. Salzenstein, a citizen of the United States, residing at Peoria, in the county of Peoria and State of Illinois, have invented a new, original, and ornamental Design for a Blouse, of which the following is a specification, reference being had to the accompanying drawing, forming part thereof.

Fig. 1 is a front view of a blouse embodying my new design;

Fig. 2 is a front view of the blouse shown in Fig. 1 with the lapel and collar portion on one side raised, showing the Shirred portion underneath;

Fig. 3 is a rear view of the blouse shown in Fig. 1;

Fig. 4 is an enlarged fragmentary front view of the blouse shown in Fig. 1, showing the shoulder shirring;

Fig. 5 is a view similar to Fig. 4 with the lapel and collar portion raised; and

Fig. 6 is a fragmentary rear view of the blouse shown in Fig. 1 showing the shirring.

The characteristic features of my design reside in the combination on the blouse disclosed of the specific patches of shirring below the drop shoulder yoke on each side of the front portion extending from the sleeve seams to points beneath the lapel notches in association with a wide band of shirring extending across the back below the back shoulder yoke and the random pressed pleats between the shirring and the waistband, all as shown.

I claim:

The ornamental design for a blouse, substantially as shown and described.

ARNOLD R. SALZENSTEIN.
